BARREL LIFTER

Willard M. Rich, Buffalo, N. Y.

Application February 14, 1946, Serial No. 647,473

2 Claims. (Cl. 294—104)

1 My invention relates in general to lifting devices, and in particular to devices of the type sometimes referred to as grapples for lifting and transporting barrels, drums, boxes, packages, or the like.

The principal object of my invention has been to provide a lifting device by which the object being handled is held in gripped position by the reaction of the weight of the object upon the lift device; and one which shall so securely grasp the object to be lifted that accidental displacement therefrom will be prevented.

Another object has been to provide a device which may be used to directly grapple for vertical lifting an object which is standing in upright attitude, or to grapple upon an object disposed in a reclining attitude for pulling the object into an upright attitude.

A further object has been to provide a lifting device which may be separately engaged with utmost facility for vertical lifting purposes upon barrels, drums, or the like which are standing close together, as in storage warehouses and the like.

Moreover, my device is provided with hoist attaching means by which the amount of the grapping action of the device may be altered for any given load.

Furthermore, my device is of such a nature that it not only saves considerable labor in the handling of objects, but it is one which may be easily attached to and detached from the objects being handled.

The invention further contemplates provision of a grapple device employing opposite load-engaging arms which are of unequal lengths.

The above objects and advantages have been accomplished by the device shown in the accompanying drawings, of which:

Fig. 1 is a perspective view of the complete device;

Fig. 2 is a side elevation thereof showing it in grappling position upon a barrel which is standing in upright position; and

Fig. 3 is a side elevational view showing the device in grappling position upon a barrel reclining in a horizontal position, preliminary to pulling the barrel to an upright attitude.

While my device is also applicable to the handling of boxes and other such objects, it is particularly adapted for use in connection with barrels, drums, and the like; and for illustrative purposes it is shown in the accompanying drawings as being used in connection therewith.

The device comprises a hook member 10 hav-

5 ing a clamp arm 11 which extends downwardly, as shown in Fig. 2, when grasping an object in vertical position, such as barrel indicated 12. A prong 13 is formed at the extreme lower end of the clamp arm 11 for engagement with the side of the barrel near its lower edge. The device also includes a gripping member 14 comprising a pair of gripping arms 15—15 which are pivotally attached to the upper end of the hook member clamp arm 11 by means of a pivot bolt 16. These gripping arms are spread outwardly from their pivotally connected ends in V-shaped manner so as to receive between their outer ends a brace 20 which serves to secure the outer ends of these arms in fixed spaced relation. A leg 21 extends downwardly from each end of the brace 20, and each leg terminates in an inwardly inclined gripping prong 22 at its free end. The hook member clamp arm 11 is considerably longer than the legs 21—21 whereby when the prong 13 is engaging the barrel at one end, the prongs 22 are disposed near the opposite end of the barrel and at its opposite side. By providing two prongs as at 22—22 and one prong as at 13, a three point contact and suspension is provided for the object being handled. Hence, the gripping action upon the object will not only be secure, but rolling of the object in the device will be prevented.

10 The hook member clamp arm 11 is formed at its upper end with an integral lifting arm 23 whereby the clamp arm and lifting arm unit 11—23 provides a substantially rigid L-shaped member. The lifting arm is disposed to extend between the gripping arms 15, and is provided 15 with two spaced hoist engaging eyes 24 and 25 formed in tabs 26 and 27, respectively, extending vertically from the lifting arm 23 and formed integrally therewith. The hook member clamp arm 11 and the hook member lifting arm 23 may 20 conveniently be formed of stock angle iron so as to insure unit rigidity thereof under load lifting operations.

25 While my device is generally applicable to various size objects or barrels, it is of advantage to have it so proportioned as to approximately fit the objects upon which it is to be used. As shown in the drawings, the clamp arm 11 is preferably of such length that when occupying the position shown in Fig. 3, the prong 13 thereof will engage 30 around one of the end edges of the barrel when the gripping member 14 is in a position of substantial parallelism with the other end of the barrel. Thus, the spaced prongs 22—22 of the last mentioned member will engage the outside 35 surface of the barrel at the opposite side and

near the opposite end thereof. A barrel, as indicated in broken lines, which is lying on its side may thereupon be pulled by the grappel device to an upright attitude by engaging the eye 25 with the hook 30 of a hoisting device such as a cable 31 depending from an electric hoist or the like. It will be seen that when the device is used in the position shown in Fig. 3, that the lifting arm 23, being arranged at an obtuse angle with the clamp arm 11, will produce sufficient leverage upon the arms 11 and 15 when attached to a hoist to lift the object. Thus, when the hoist is operated the levering action of the device will securely hold the prong 13 in position engaging around the far edge of the barrel while the prongs 22—22 are pressed into the opposite side portions of the barrel. Then, as the hoist continues to pull upwardly upon the cable 31 the barrel will be swung to a substantially vertical attitude, whereupon it may be either transported to any desired place or lowered and released to stand vertically in substantially the same place from which it was elevated.

When the device is to be used simply to elevate and transport a barrel previously occupying a vertical position as indicated in Fig. 2, it is preferable to use the eye 26 for engagement with the hoist hook 30. When so used, it is not necessary that the prong 13 of the hook member clamp arm 11 engage under the bottom edge of the barrel (which cannot be accomplished unless the barrel is tipped somewhat to one side), but such prong may be engaged against the side surface of the barrel near its lower end whereupon it will become firmly embedded in the material of the barrel by reason of the lever action of the hook member 10 around the pivot bolt 16 which is held in substantially rigid position by means of the gripping member 14 after the prongs 22—22 thereof have become embedded in the material at the opposite side and end of the barrel. Further pulling of the cable 31 will cause the prongs to be even more tightly forced into the barrel material, whereby it may be lifted and transported to any desired place without the possibility of accidental dropping of the barrel.

If desired, the lifting arm 23 may be provided with only one hoist engaging eye when designed for use when handling barrels or other objects disposed either in horizontal or vertical attitudes. Obviously, this as well as other modifications of the details herein shown and described may be made without departing from the spirit of my invention, or the scope of the appended claims, and I do not wish to be limited to the exact embodiment shown and described.

I claim:

1. In combination, a barrel and a lifting device for hooking engagement with said barrel, said device comprising a pair of rigid spaced gripping arms extending across one end of the barrel and formed at their free ends with prongs for hooking into one side of said barrel and formed at their opposite ends with pivot apertures, cross arm means interconnecting said gripping arms, a pivot pin extending through said apertures, a hook member having a clamp arm and an integral lifting arm arranged at an angle thereto, said clamp arm being disposed to extend along the opposite side of said barrel and having a prong at its free end hooked for engagement with the opposite side wall of said barrel at a position above the lower edge thereof, said lifting arm being disposed to extend over the first mentioned end of said barrel, and said hook member having pivotal connection with said pivot pin at a point near the juncture of the clamp arm and lifting arm portions thereof.

2. In combination, a barrel and a lifting device for hooking engagement with said barrel, said device comprising a bifurcated gripping arm device extending across one end of the barrel and formed at its free ends with prongs for hooking into one side of said barrel and formed at its opposite end with a pivot aperture, a pivot pin extending through said aperture, a hook member having a clamp arm and an integral lifting arm arranged at an angle thereto, said clamp arm being disposed to extend along the opposite side of said barrel and having a prong at its free end for hooked engagement with the opposite side wall of said barrel at a position above the lower edge thereof, said lifting arm being disposed to extend over the first mentioned end of said barrel, and said hook member having pivotal connection with said pivot pin at a point near the juncture of the clamp arm and lifting arm portions thereof.
